PAPER SHAKE APPARATUS AND METHOD

Application filed February 15, 1929. Serial No. 340,216.

This invention pertains to the manufacture of paper and more particularly to the shaking of the stock or pulp stream in machines of the well-known Fourdrinier type. In paper manufacture it is desirable, in order to effect interlacing of the pulp or cellulose fibers, to agitate the web or stream of pulp as it passes over the wire or screen of the Fourdrinier machine. This agitation of the pulp stream is accomplished by shaking laterally the Fourdrinier wire or screen, together with other parts of the machine. Such shaking of the machine subjects it to considerable wear and tear, lessens the life of the wire or screen, and generally causes depreciation which becomes especially objectionable when the highly expensive character of such machines is considered.

A prime object of my invention is to provide for the effective agitation of the pulp stream without shaking the Fourdrinier wire or other parts of the machine. This I accomplish by applying agitating impulses to the upper surface of the pulp stream as it flows along the Fourdrinier wire. In addition to obviating the shaking of the machine, increasing the life of the wire, and substantially lessening the depreciation of the costly Fourdrinier mechanism, my invention further provides for imparting turbulence to the stream in various directions with resultant improvement in the interlacing of the fibers and consequent strengthening of the paper. Through my invention, moreover, the pulp stream may be subjected to the same conditions of agitation substantially over its entire area, which results in greater uniformity of the sheet of paper across the wire. An additional advantage resides in the fact that the invention requires the expenditure of less power than is necessary for shaking the machine. In addition, the invention involves other features and advantages which will be hereinafter set forth.

In the accompanying drawings, wherein I have illustrated a form of apparatus suitable for carrying out my invention:

Fig. 1 is a longitudinal vertical sectional view taken on line 1-1 of Fig. 2, and showing apparatus embodying my invention ap-

plied to a standard Fourdrinier paper machine.

Fig. 2 is a plan view of the apparatus.

Fig. 3 is a transverse vertical sectional view taken on line 3-3 of Fig. 2, and

Fig. 4 is a view of a detail.

Referring to the drawings, the reference numeral 2 designates generally the so-called wet-end portion of a Fourdrinier paper-making machine of standard construction comprising side frames 3 supporting the usual table rolls 4. The Fourdrinier screen or wire is shown at 5 and is caused to travel in the usual way over the breast-roll 6 and table rolls 4. The stock, or stream of water and pulp fibers, flows from the head box 7 to the screen 5 and is carried along by said screen. The customary deckle straps are indicated at 8, while 9 designates one of the deckle pulleys.

In carrying out my invention I provide for the imparting of shaking or agitating impulses to the upper surface of the pulp stream; for which purpose I have by way of example illustrated an apparatus which may take the following form:

A table or platform 10 is mounted at such distance above the Fourdrinier wire 5 as to contact with the upper surface of the stock or pulp stream as the latter flows from the head box 7 between said table 10 and wire 5. The shaking of the upper surface is sufficient to effect agitation of the stream throughout its entire depth; and I prefer that the table should not extend a substantial distance below the surface of the pulp stream. The lower surface of the table which touches the stock or pulp stream may be made of rustless alloy steel or of a rubber composition having a low coefficient of friction. Preferably, the table itself should be made of light material, as, for example, balsa wood or aluminum.

I have shown the table suspended from bridge members 11, two of which members are shown; each member comprising a pair of channel bars 11' 11''. Said bridge members are secured at their opposite ends to the respective side frames 3. Connecting the bridge members 11 and platform 10 are a

100

plurality of vibrators 12. These vibrators may be of any standard type, either electrically or pneumatically operated. Each of the vibrators 12 is connected at its upper end to one of the bridge members 11 and at its lower end to a suitable bearing on the platform 10. Through said vibrators the platform 10 is reciprocated vertically.

Also connected to said platform or table 10 are vibrators 13 which may be of the same type as the vibrators 12 for reciprocating said platform in a horizontal plane transversely of the Fourdrinier wire 5. The vibrators 13 are suitably secured to the side frame member 3 and at their other ends may be connected to bearings on the platform 10. Thus, through the vibrators 12 and 13 the table 10 may be reciprocated or vibrated both vertically and in a horizontal direction transverse to the travel of the stock or pulp stream. Also, vibrators 14 may be provided for reciprocating the platform 10 in a horizontal plane longitudinally of the Fourdrinier wire. The vibrators 14 may be of the same type as the vibrators 12 and 13; each vibrator 14 being shown connected at one end to a suitable bearing on the platform 10 and at the other end to a corresponding pair of bracket members 15 depending from bridge member 11. The number of vibrators employed as well as the type of vibrator may of course be varied as desired. Also, the vibrators may be connected to the table 10 in any of a variety of ways; the connection illustrated comprising a transversely extending member 16 on the end of the reciprocatory rod 17 of the vibrator and mounted in bearings in a bracket 18 on said table. As shown, each of the bridge members 11 comprises two channel bars 11', 11'', extending parallel to each other, and the vibrators 12 may be secured to said bridges through pins 19 extending through the upper ends of said vibrators and into the adjacent beams. The vibrators 14 are similarly shown pinned to the adjacent depending bracket elements 15.

It will be seen from the foregoing description that through the vibrators 12, 13, and 14 the platform or table 10 will be vibrated or reciprocated (1) vertically, (2) horizontally in a direction transverse to the line of travel of the pulp stream, and (3) in the line of travel of said stream. In this way the pulp stream is effectively agitated simultaneously in several directions and the pulp fibers are thereby interlaced more thoroughly than has heretofore been the case. Of course, if desired, one or more of the sets of vibrators may be omitted and the stream agitated only in one or two of the directions above indicated. The vibrators may act in synchronism or otherwise as desired, and may have either the same or different frequencies of vibration. The frequencies, as well as the amplitudes of vibration, may moreover be varied.

Motion of the table in all directions under the influence of the vibrators may be readily permitted by the elasticity of the material of which the table is composed; or, if desired, provision for such vibration may readily be made by providing sufficient slack or lost motion in the bearings which connect the vibrators with said table.

The bottom of the table 10 may be stepped as shown at 20, in a manner similar to a hydroplane, so as to decrease the friction between the water and the table. If desired the table may be constructed with perforations or air passages 30 communicating with the pockets formed by said steps, whereby resistance to movement of said table may be further decreased. The inclinations of the steps 20 may be varied as desired, or the steps may be omitted.

I have also provided for raising or lowering the table to vary the distance between its lower surface and the Fourdrinier wire 5. This may be accomplished in any one of various ways as by raising or lowering the bridge members 11 through means such as that illustrated in Figs. 3 and 4.

As shown in said figures, a vertical screw 21 is provided at each end of each bridge member; each screw being threaded through a cross piece 22 secured to the adjacent channel bars 11', 11''. At its lower end said screw rests upon a plate 23 mounted on member 3' of the side frame 3. At their lower ends the channel bars aforesaid are shown provided with inwardly and downwardly projecting flanged portions 24, 25 which form guide brackets on opposite sides of the screw 21; while bracket members 24', 25' are shown secured to said flanged portions. Bolts 26 mounted on the side frame, and extending through the plate 23 and through laterally extending lower portions of the brackets or angle irons 24', 25' serve to limit the upward movement of the bridge member and are readily adjustable to permit said member to be raised. An aperture 31 in side frame 3 affords ready access to the heads of the bolts 26. It will be seen that through screws 21 the bridge members 11, and hence table 10, may be raised at either end so that the distance between either end of the table and the pulp stream may be regulated as desired. This is advantageous in that the stream of water thins out as it flows along, due to passage of water through the wire screen 5.

It will be seen that I provide for agitating the pulp stream without shaking either the Fourdrinier wire or any other part of the Fourdrinier machine, thus avoiding racking of the delicate screen and obviating wear and tear and depreciation of the machine generally. It may also be noted that the application of pressure to the screen in a vertical plane by the vibrators 12 tends to force water from the stream through the wire mesh,

whereby the passage of water through the screen may be substantially expedited.

It will further be evident that my invention enables more uniform sheets of paper to be produced, since the total area of the stream may be subjected to the same conditions of vibration. Also, more thorough interlacing of fibers is effected; and interlacing in all directions may be obtained so that the sheets 10 may be as strong crosswise as lengthwise, a condition not attained by the shake mechanisms employed heretofore. Furthermore, it is manifest that less power is required to shake the table 10 than is necessary to impart the desired agitation to Fourdrinier machines.

It will be obvious that in lieu of a single table 10 a multiple-unit or series of such tables and associated vibrators may be employed for agitating the stock on the Fourdrinier wire; and it will be further apparent that numerous other modifications may be made within the scope of my invention.

The terms and expressions which I have 25 employed are used as terms of description and not of limitation, and I have no intention, in the use of such terms and expressions, of excluding any mechanical equivalents of the features shown and described or portions thereof, but recognize that various structural modifications are possible within the scope of the invention claimed.

What I claim is:

1. The method of agitating a stream of pulp which comprises applying impulses to the upper surface of the stream.
2. The method of effecting interlacing of fibers in a stream of pulp on a Fourdrinier wire which consists of agitating said stream 40 independently of said wire as said stream flows along said wire.
3. The method of effecting interlacing of fibers in a stream of pulp on a Fourdrinier wire which comprises simultaneously agitating said stream independently of the wire in different planes as said stream travels with said wire.
4. The method of effecting interlacing of fibers in a stream of pulp on a Fourdrinier 50 wire which comprises simultaneously agitating said stream both vertically and horizontally relatively to said wire.
5. The method of effecting interlacing of fibers in a stream of pulp on a Fourdrinier 55 wire which comprises simultaneously agitating said stream in directions substantially at right angles to each other independently of said wire as said stream travels with said wire.
6. The method of effecting interlacing of fibers in a stream of pulp on a Fourdrinier wire which comprises agitating simultaneously 60 said stream in three directions at right angles to each other.
7. The method of effecting interlacing of

fibers in a stream of pulp on a Fourdrinier wire which comprises simultaneously agitating said stream both vertically and horizontally in a direction transverse to the travel of said wire.

8. The method of effecting interlacing of fibers in a stream of pulp on a Fourdrinier wire which comprises applying impulses to the upper surface of said stream as the latter flows along the wire.

9. In a paper-making machine, the combination with a traveling screen for conveying a stream of pulp, of means for agitating the pulp stream during the travel thereof along said screen without shaking said screen.

10. In a paper-making machine, the combination with a traveling screen for conveying a stream of pulp, of means independent of said screen for agitating said stream transversely of the line of travel of said screen 85 during the passage of said stream along said screen.

11. In a paper-making machine, the combination with a traveling screen for conveying a stream of pulp, of means for automatically 90 applying pressure vertically to said pulp stream during its travel along said screen.

12. In a paper-making machine, the combination with a traveling screen for conveying a stream of pulp, of means for intermittently applying vertical pressure to said pulp stream during its travel along said screen.

13. In a paper making machine, a Fourdrinier wire, and means above said wire for applying impulses to the upper surface of the pulp stream to agitate the latter.

14. In a paper making machine, a Fourdrinier wire, a table member above said wire supported for contact with the pulp stream, and means for reciprocating said table member.

15. In a paper making machine, a Fourdrinier wire, a table member supported above said wire for contact with the pulp stream, and means for vibrating said table member 105 both vertically and horizontally.

16. In a paper making machine, a Fourdrinier wire, a table element supported above said wire for contact with the pulp stream, the under surface of said element being provided with inclined steps, and means for vibrating said element to agitate the pulp stream.

17. In a paper making machine, a Fourdrinier wire, and means for simultaneously shaking the pulp stream and forcing water from said stream through said wire.

18. In a paper making machine, a Fourdrinier wire, and means for simultaneously shaking the pulp stream independently of said wire and forcing water from said stream through said wire.

19. In a paper making machine, a Fourdrinier wire, a table member supported over 130 said wire for contact with the pulp stream,

means for vibrating said table member, and means whereby said table may be positioned at different heights above said wire.

20. In a paper making machine, a Four-drinier wire, a table member supported over said wire for contact with the pulp stream, means for varying the height above the wire of one end of said table with respect to the other.

10 21. In a paper making machine, a Four-drinier wire, a table element supported above said wire for contact with the pulp stream, the undersurface of said element being provided with inclined steps forming pockets, 15 and said element being further provided with air passages communicating with said pockets, and means for vibrating said element to agitate the pulp stream.

22. The method of agitating a stream of pulp which comprises applying impulses to the upper surface of the stream transversely to the direction of travel of the stream.

23. The method of effecting interlacing of fibers in a stream of pulp on a Fourdrinier wire which consists of applying intermittent impulses to said stream independently of the wire and in a direction transverse thereof as said stream flows along said wire.

In testimony whereof, I have signed my name to this specification this 12th day of February, 1929.

HENRI G. CHATAIN.
